PNEUMATIC TIRE

Russel O. Rice, Birmingham, Charles M. Chupa, Dearborn Township, Wayne County, and Carl F. Smajd, St. Clair Shores, Mich., assignors to United States Rubber Company, New York, N.Y., a corporation of New Jersey

Filed Oct. 7, 1959, Ser. No. 57,853

Term of patent 14 years

(Cl. D90—20)

Fig. 1

Fig. 2

Fig. 1 is a perspective view of a pneumatic tire embodying our new design, it being understood that the full line portion is repeated throughout the circumference of the tire shown by means of broken lines;

Fig. 2 is an enlarged fragmentary side elevational view of the full line portion of Fig. 1;

Fig. 3 is an enlarged fragmentary plan view of the full line tread portion of Fig. 1;

Fig. 4 is a sectional view taken substantially on the plane indicated by line IV—IV of Fig. 3;

Fig. 5 is a detailed sectional view taken substantially on the plane indicated by line V—V of Fig. 4;

Fig. 6 is a detailed sectional view taken substantially on the plane indicated by line VI—VI of Fig. 4, and

Fig. 7 is a detailed sectional view taken substantially on the plane indicated by line VII—VII of Fig. 4.

Fig. 8 is a fragmentary sectional perspective view taken substantially on the plane indicated by VIII—VIII in Fig. 3.

The characteristic features of the design for the tire disclosed reside in a tread having continuous cross lugs and circumferentially-extending, transversely-slotted, sub-tread ribs spanning the space between said cross lugs as shown.

We claim:

The ornamental design for a pneumatic tire, substantially as shown and described.
